UNITED STATES PATENT OFFICE.

FRANK RAUCH, OF SPRINGFIELD, MASSACHUSETTS.

FOUNTAIN-PEN LIGHT.

1,228,132.

Specification of Letters Patent.

Patented May 29, 1917.

Application filed August 22, 1916. Serial No. 116,291.

To all whom it may concern:

Be it known that I, FRANK RAUCH, a subject of the King of Hungary, residing at Springfield, in the county of Hampden and State of Massachusetts, have invented certain new and useful Improvements in Fountain-Pen Lights, of which the following is a specification.

This invention relates to new and useful improvements in fountain pen lights.

The primary object of the invention is the provision of a light attachment for pen holders especially adapted for use with fountain pens, whereby a person may write 15 with the same in the dark when found desirable.

A further object of the device is the provision of a battery light carried by a pen holder arranged with a switch member 20 whereby the light may be turned on when desired for giving sufficient light for writing purposes adjacent the pen carried by the device.

A still further object of the invention is 25 the provision of a fountain pen having an electric lamp arranged adjacent the writing point thereof and with a switching means for controlling the lamp at a convenient point upon the pen holder.

30 In the drawing forming a part of this application and in which like reference characters refer to corresponding parts throughout the several views:

Figure 1 is a side elevation of the fountain pen in its closed position.

Fig. 2 is a similar view thereof with the cap removed.

Fig. 3 is a central longitudinal sectional view through the same.

40 Fig. 4 is an end view of the fountain portion of the pen holder.

Fig. 5 is an end elevation of the removable casing portion of the holder with a battery arranged therein.

45 Fig. 6 is a perspective view of the inner end portion of a battery employed with the device, and

Fig. 7 is an enlarged detail sectional view illustrating the switch member.

50 The present lamp attachment being designed for fountain pens is herein illustrated in connection with a fountain pen in the form of a pen holder 10 having a removable cap 11, the holder being supplied with a writing pen 12 supplied with ink from a reservoir 13 within the main portion 14 of

the holder in substantially the usual manner. A removable screw 15 is arranged in the rear end 16 of the pen holder portion 14 for the purpose of filling the reservoir 13 with ink when desired.

A tubular casing portion 17 has screw threaded connection with the portion 14 being adapted to contain a suitable dry battery 18, a spring 19 being employed between the closed end 20 of the casing 17 and the said battery for resiliently maintaining the terminals 21 and 22 of the battery in normal resilient engagement with the terminal binding posts 23 and 24 respectively carried by the said body end 16.

A diminutive incandescent lamp or bulb 25 is removably screw-threaded in the forward end 26 of the body 14 adjacent the writing pen 12. The binding post contact 23 is normally electrically connected with an angular spring terminal 27 by means of a wire 28, the central contact 37 of the lamp 25 being normally in contact with the said spring 27. The said wires 28 and 29 are arranged within an eccentrically positioned longitudinal bore 36 of the body 14. The binding post 24 is normally electrically connected by means of a wire 29 with a spring 30 adjacent the said contact member 27. A switch closer 31 is slidably arranged in the side slot 33 in the body 14 and has a pin 33 upon which the spring 30 rides, while a contact arm 34 is carried by the member 31 adapted to engage the shell 35 of the lamp 25 when the circuit closer is moved forwardly as illustrated in Fig. 3 of the drawing, the same being out of contact and the switch open when in the dotted line position illustrated in Fig. 7.

It will be understood that the switch member 31 is normally in its open retracted position, the battery 18 being in its position within the casing portion 17 connected with the body portion 14. When desiring to employ the pen 12 for writing in the dark, the switch member 31 is moved forwardly closing the electrical connections between the lamp 25 and the battery 18, whereby the said lamp is lighted shedding sufficient light upon the point 12 and the writing surface to allow the pen to be readily used. The removable cap 11 is normally arranged upon the body portion 14 completely overlying the pen 12, lamp 25 and the switch 31. The casing 17 may be removed when desired and the new battery 18 inserted, it only being

necessary when replacing the same to make assurance that the contacts 21 and 22 of the battery are engaged with the binding posts 23 and 24 upon the end 16 of the body member 14 of the pen holder.

What I claim as new is:—

In a fountain-pen light, a body member, a casing applied to one end of said body-member and containing an electrical source 10 of supply, said electrical source of supply having poles in a head thereof, said body-member having a pen-holder therein, whose rear head is provided with terminal binding posts, a resilient member within said body-member exerting pressure to retain said poles and binding posts in engagement with

each other, an electrical lamp positioned in one end of said body-member, adjacent the pen, an angular spring-terminal in engagement with a contact of said electrical lamp, 20 a spring adjacent said angular terminal, a slideable switch-closer having a contact-arm adapted to engage the electrical lamp-shell, said spring being arranged to ride upon a pin projecting from said switch-closer as 25 the latter is actuated, one of said binding posts being wired to the spring having engagement with said slideable switch-closer, the other binding post being wired to said angular spring terminal.

In testimony whereof I affix my signature.

FRANK RAUCH.
